**1-ALKYLPHENYL-2,2-DI LOWER ALKYL-4,6-DI-
IMINO-HEXAHYDRO-s-TRIAZINES**

Daniel Elmer Nagy, Stamford, Conn., assignor to American Cyanamid Company, Stamford, Conn., a corporation of Connecticut.

ation of Connecticut
No Drawing. Filed Oct. 17, 1961, Ser. No. 145,768
6 Claims. (Cl. 260—249.9)

This invention relates to new and useful alkyl-phenyl hexahydrotriazines and processes for their preparation. The invention is particularly concerned with the preparation of a new class of higher alkylated derivatives of phenyl hexahydrotriazine which demonstrate a high level of antibacterial, antifungal, and antialgal activity in a diversity of media.

The novel compounds of the present invention may be generally depicted as alkylated hexahydrotriazines of the following general structures embracing both tautomeric forms:

and acid addition salts and isomers thereof particularly the isomeric forms:

wherein R represents a substituent selected from the group consisting of a higher alkyl group having from 8 to about 18 carbon atoms and also an alkanoyl group; R' represents a substituent selected from the group consisting of hydrogen and methyl; and R'' represents a substituent selected from the group consisting of a lower alkyl group having from 1 to about 7 carbon atoms and a hydroxy lower alkyl.

In the tautomeric forms I, II, III, and IV illustrated above, all forms are equally active biocidal agents. However, the forms II and IV are generally considered to be the more stable forms although this is merely a matter of degree.

By the term "higher alkyl" as it is employed to define the R substituent it is intended to represent alkyl groups of the aliphatic series containing from C₈-C₁₈ carbon atoms which may be either in straight or branched chain conformation. This would, of course, embrace such substituents as octyl, nonyl, decyl, undecyl, dodecyl, tridecyl and branched chain isomers thereof. On the other hand, the term "lower alkyl" is intended to refer to the lower members of the series wherein C₁-C₇ carbon atoms are contained either in straight or branched chain conformation. All of the well known members of this series such as methyl, ethyl, propyl, butyl, pentyl, hexyl, and heptyl

would thus be included. In the

would thus be included. In the case of the R substituent it is preferred that the substitution be in the para position in the phenyl ring although it is within the scope of the invention to effect substitution at any of the available positions in the phenyl ring.

By the term "hydroxy lower alkyl" it is intended to embrace polyhydroxy groups having from about 2 to 7 carbon atoms. By the term "alkanoyl" it is intended to refer to such carbonyl groups containing from about 2 to 22 carbon atoms and includes such groups as propionyl, butyryl, pentanoyl, hexanoyl, octanoyl, dodecanoyl, octadecanoyl and the like.

It is known that a phenyl hexahydrotriazine has utility in pharmaceutical applications as an agent for the treatment in humans of malaria and the like maladies of the blood. However, such compounds have never demonstrated any utility in the inhibition of bacterial, algal, or fungal growth and, in fact, when tested are found to be devoid of such activity. Quite unexpectedly, however,

20 devoid of such activity. Quite unexpectedly, however, when one prepares the hitherto unknown higher alkyl derivatives of a phenyl hexahydrotriazine as illustrated above this series of compounds is found to exhibit a high level of toxicity against a broad spectrum of degrading microorganisms which uncontrolled will rapidly deteriorate various materials and industrial systems which will tolerate their growth.

tolerate their growth.

It is the principal object of the invention, therefore, to provide the art with a novel class of alkylated phenyl hexahydrotriazines and a method for their manufacture.

It is a further object to provide as a novel antimicrobial agent the novel class of alkylated phenyl hexahydrotriazines disclosed.

It is a still further object to disclose a new method for the treatment and control of microbiological pests of both plant and animal origin. These and other more specific objects of the invention will become apparent as the description of the invention is further elaborated.

The present invention is based on the discovery that the novel higher alkylated phenyl hexahydrotriazines can be prepared by reacting a higher alkylated phenylbiguanide hydrochloride with at least a molar equivalent of a ketone or aldehyde. The reaction is generally conducted in the presence of an inert solvent such as methanol or the like under reflux conditions for the solvent. The product obtained is recovered by evaporation of the solvent after washing with saline solution to remove impurities. It can be further purified by solution in a recrystallization solvent mixture such as toluene-isopropanol and the like to obtain the novel compounds of the invention.

In the case where it is desired to prepare the isomeric form of the novel compounds of this invention, one first adds from 0.05-1 mole of hydrochloric acid to the alkylated phenylbiguanide hydrochloride. It is preferred to remove any water added with the hydrochloric acid prior to reaction with the ketone by suspending the reactants in benzene and azeotropically distilling to remove any water present. Acetic acid is added as the solvent in place of methanol and the procedure is continued as above indicated to obtain the pure product.

Although methanol is the preferred solvent for the reaction, a number of equally useful inert solvents such as ethanol, cellosolve, and the like may be also employed. The time of reaction will vary with the reflux conditions and inert solvent employed, but generally speaking the

reaction will be completed within 8 to 24 hours for most, if not all, of the reactants employed.

Moreover, it is an important aspect of the present invention that in the preparation of the novel compounds a ketone such as acetone when employed in excess as a reactant has a dual function of performing as a solvent. Other ketones which may be employed in the same manner are methyl ethyl ketone, methyl isobutyl ketone, cyclohexanone, and the like which demonstrate excellent solvent properties.

It is also within the scope of the general preparation to add a substituted aniline salt and dicyandiamide to the ketone to form the alkyl substituted phenylbiguanide in situ and effect a reaction with the ketone. This may be illustrated by reference to the following general equation wherein the ketone employed is dimethyl ketone and methanol is employed as an additional solvent. The values for R are, of course the same as its values indicated above. The use of this particular variant of the general procedure will be dictated by the choice and availability of reagents.

We prefer to prepare our novel compounds by the general reaction:

wherein the values for R, R' and R'' are as above stated and the aldehyde or ketone reactant is preferably acetone although it is within the scope of our invention to employ as the carbonyl containing compound such aldoses as glucose and the like as well as aldehydic sugars or ketoses such as fructose or the like. In the latter case the R'' as illustrated above will represent a polyhydroxy function on the final product prepared.

A typical preparation of 1-dodecylphenyl-2,2-dimethyl-4,6-diimino-hexahydro-s-triazine (1-dodecylphenyl-2,2-dimethyl-4,6-diamino-1,2-dihydro-s-triazine) hydrochloride is conducted as follows. Dodecylphenylbiguanide hydrochloride (24.6 grams) is mixed with concentrated HCl (3.3 ml.) and 125 ml. of acetone. These components are refluxed overnight and the crystalline material formed recovered by crystallization. A 10 gram yield of the final product is obtained.

It has been found that when materials such as leather goods are impregnated with about 1% or less of the instant compounds they are rendered mildew proof. Incorporation of quantities of 0.5 to 1% in either oil or water based paint formulations will render them mildew proof after application on a given surface. In addition to this for those paint formulations which contain casein and latex and are thus subject to decomposition while in the container in storage the instant compounds will preserve these from such degradation when added at the same dosage levels as indicated above.

The instant novel antimicrobial agents may be added to or incorporated in the material they are destined to preserve by means of dipping, dusting, spraying or the like or alternatively by direct addition into the formula or system to be protected.

While it is preferred to employ the novel compounds of the invention in an aqueous or alcohol carrier vehicle, since they are both water and alcohol soluble they may, in a given instance, be admixed with other ingredients such as diluents, carriers and the like. Or if desired they may be placed in a formulation containing a surface active agent such as any of a number of such well known anionic, cationic, or nonionic agents.

The invention will be further illustrated by the following examples of specific methods of preparation of some of the representative members of the series. Also, a brief view of the relative antimicrobial activity of a few representative members of applicant's class of compounds as compared to the known unsubstituted phenyl hexahydrotriazines of the prior art will be presented. This will further demonstrate the truly unexpected nature of applicant's discovery.

It must be borne in mind that these several examples are intended only to illustrate the invention in more specific terms and are not intended to limit its scope in any manner. For a proper definition of the scope of applicant's invention, reference may be had to the several appended claims.

EXAMPLE 1

1-dodecylphenyl-2-n-hexyl-4,6-diimino-hexahydro-s-triazine hydrochloride

Reflux 0.128 mole of 1-dodecylphenylbiguanide hydrochloride, 0.2 mole of heptaldehyde and 2 ml. of concentrated hydrochloric acid in 150 ml. of methanol for about 30 hours. Filter off the crystals which form when the solution is cooled to a temperature of 0-5° C. Collect and recrystallize from isopropanol to obtain the product of this example. M.P. above 300° C. in yield about 70%.

EXAMPLE 2

1-dodecylphenyl-2,2-dimethyl-4,6-diimino-hexahydro-s-triazine hydrochloride

Heat 0.0428 mole of dodecylphenylbiguanide hydrochloride, 0.145 mole of acetone and 1 ml. of concentrated hydrochloric acid at 50-60° C. in 100 ml. of methanol for 8 hours with constant stirring. The solution is concentrated by evaporation to about 50 ml. at reduced pressure and filtered to give a finely divided white powder in 80% yield which is the product of this example in its isoform M.P. 200-202° C.

Alternatively the 1-dodecylphenyl-2,2-dimethyl-4,6-diimino-hexahydro-s-triazine hydrochloride of this example may be prepared in the following manner:

Dissolve 0.05 mole of dodecylaniline in toluene and treat with 0.055 mole of dry hydrogen chloride gas over a one half hour period. Maintain the temperature of the reaction mixture at 80° C. and add 0.0525 mole dicyandiamide in small portions over a one half hour period. After addition of the dicyandiamide, increase the temperature to 90° C. and maintain for 3 hours. Cool the solution slowly to about 50° C. and add 0.10 mole of acetone. Heat this reaction mixture to 70° C. for 8 hours following the addition of the acetone. Cool the solution and separate out a finely divided white powder which is the product of this example. M.P. 200-202° C.

EXAMPLE 3

1-octadecylphenyl-2,2-dimethyl-4,6-diimino-hexahydro-s-triazine

Dissolve 1.0 mole of octadecylaniline in 200 ml. of isopropanol and treat with 1.10 mole of hydrogen chloride gas over a period of one half hour. Increase the temperature to 80° C. and add 1.05 mole dicyandiamide in small

portions over a period of one half hour. Increase the temperature to 90° C., maintain for 3 hours and reduce to about 50° C. Add 1.05 mole of acetone and raise the temperature to 75° C. where it is maintained for about 8 hours. Dilute the reaction mixture with isopropanol and crystallize by removing about half of the solvent under vacuum to yield the hydrochloride salt of the compound. Careful addition of 1.10 mole of ammonium hydroxide dropwise at room temperature yields the free base which is the product of this example.

EXAMPLE 4

2,2-dimethyl-4-dodecylphenylimino-6-imino-hexahydro-s-triazine hydrochloride

A. *Dodecylphenylbiguanide hydrochloride*.—Dilute 0.5 mole of concentrated hydrochloric acid (50 grams); to 100 ml. with water. Suspend 0.4 mole dodecylaniline and 0.6 mole dicyandiamide in 100 ml. of a 50% water-isopropanol mixture. Heat to 90° C. and add the dilute acid solution slowly over 1½ hours. Heat the solution for 2 hours longer. Cool the solution and dilute with 100 ml. of benzene and 75 ml. of isopropanol in a separatory funnel after washing with 20% saline solution to remove impurities. Add additional isopropanol during the washing procedure to insure the separation of the layers in the funnel. Separate off the upper layer containing 436 ml. of the mixture which contains the dodecylphenylbiguanide hydrochloride starting material for use in Part B of the example.

B. *2,2 dimethyl - 4 - dodecylphenylimino-6-imino-hexahydro-s-triazine hydrochloride*.—Evaporate 0.1 mole of dodecylphenylbiguanide hydrochloride of Part A (115 ml.) to remove the solvent. Add 100 mls. of benzene and 2.0 ml. of hydrochloric acid and azeotrope to remove water. Distill the benzene off and take up the residue in 200 ml. of acetic acid and 20 ml. of acetone. Heat this solution at 90° C. for about 16 hours. Remove the solvents by evaporation, and take the product up in a mixture of toluene and isopropanol and wash with 30 ml. of saline solution. The upper layer is removed and vacuum distilled to give 4.4 grams of the product of this example. M.P. 86–88° C. The product formed is referred to as the normal form and is soluble in acetone, benzene and slightly soluble in water.

EXAMPLE 5

1-dodecylphenyl-2,2-dimethyl-4,6-diimino-hexahydro-s-triazine hydrochloride

Distill off 115 ml. of the dodecylphenylbiguanide hydrochloride solution of the Part A of the preceding example. Add 100 ml. of benzene and azeotrope to remove 2.5 ml. of water. Then add 2.0 ml. of concentrated hydrochloric acid and azeotropically distill to remove 1.6 ml. of water. The benzene is then distilled off. Add 100 ml. of methanol and 22 ml. of acetone and reflux at 64° C. for 18 hours. Vacuum distill off the methanol and suspend the product recovered in 250 ml. of acetone. The insoluble residue weighs 9.5 grams. Distill off the acetone and take the product up in benzene and precipitate with hexane. A second fraction of insolubles of 9.1 grams is obtained. Both fractions exhibit a melting point of 195–202° C. and are the product of this example in its isomeric form.

EXAMPLE 6

2-methyl-2-isobutyl-4-dodecylphenylimino-6-imino-hexahydro-s-triazine hydrochloride

Treat 115 ml. of dodecylphenylbiguanide hydrochloride of Part A of Example 4 as in the preceding examples. After the benzene is distilled off take up the residue in 50 ml. of methyl isobutyl ketone and 200 ml. of glacial acetic acid. Heat at 96° C. for 24 hours. The crude product of this example is obtained by vacuum evaporation of the solvents. It is only very slightly soluble in

water and readily soluble in isopropanol. During vacuum drying at 90° C. it is a thick liquid but upon cooling becomes a glassy solid.

EXAMPLE 7

1-octylphenyl-2,2-dimethyl-4,6-diimino-hexahydro-s-triazine hydrochloride

Admix 0.025 mole (6.0 grams) of 4-n-octylaniline hydrochloride, 0.027 (2.3 gram) of dicyandiamide and 10 ml. of acetone with constant stirring at room temperature for 14 hours. Chill the resulting dark amber solution to obtain 5.5 grams (60% yield) of the hexahydrotriazine of the example in four portions. Recrystallize from acetone to obtain the product of this example. M.P. 197–199° C.

Analysis.—Calc'd for $C_{19}H_{32}N_5Cl$: C, 62.34; H, 8.81; N, 19.14; Cl, 9.69. Found: C, 62.18, 62.10; H, 8.91, 9.03; N, 19.06, 19.28; Cl, 9.80, 9.65.

EXAMPLE 8

1-octanoylphenyl-2,2-dimethyl-4,6-diimino-hexahydro-s-triazine hydrochloride

Stir for 18 hours a mixture of 0.025 mole (6.4 grams) of 4-n-octanoylaniline hydrochloride; 0.027 mole (2.3 grams) of dicyandiamide and 30 ml. of acetone in 15 ml. of methanol at room temperature until the solution turns orange color and a precipitate forms. The overall stirring time is about 24 hours. Chill the mixture to obtain 1.9 grams of product in two crops and spontaneous evaporation of the solvent yields another 5.4 grams for a total yield of 7.3 grams (77%). Recrystallize this crude product twice from a 1 to 3 mixture of methanether and once from water to recover the product of this example. M.P. 184–186° C.

Analysis.—Calc'd for $C_{19}H_{30}N_5OCl$: C, 60.07; H, 7.96; N, 18.44; Cl, 9.34. Found: C, 60.03, 59.94; H, 8.10, 7.98; N, 18.30, 18.05; Cl, 9.18, 9.12.

EXAMPLE 9

4-dodecanoylphenylimino-2-methyl-2-isobutyl-6-imino-hexahydro-s-triazine hydrochloride

To 0.1 mole (39.5 grams) of dodecanoyl phenyl biguanide hydrochloride and 150 ml. of benzene add 2.0 ml. of concentrated hydrochloric acid. Azeotropically distill this mixture until 1.6 ml. of material is removed. After distilling the benzene add 50 ml. of methyl isobutyl ketone and 200 ml. of glacial acetic acid, and heat the solution at 96° C. overnight. The test for the presence of biguanides, using copper sulfate and alkali as test reagents, will give a negative reaction indicating the absence of the starting biguanide.

Vacuum evaporate the above solution to obtain a quantitative yield of the crude product of the example which is an amorphous solid, soluble in isopropanol from which it is purified by recrystallization.

EXAMPLE 10

4-octadecanoyl phenylimino-2-methyl-2-isobutyl-6-imino-hexahydro-s-triazine hydrochloride

By substituting mole equivalent quantities of octadecanoyl biguanide hydrochloride for the dodecanoyl phenyl biguanide hydrochloride of Example 9 and processing as otherwise indicated the compound of this example may also be prepared in good yield.

While only a few of the alkanoyl substituted members of the novel group of substituted hexahydro-s-triazines have been shown, it is believed that these are representative of the broad class of such substituted derivatives included within the concept of the invention.

EXAMPLE 11

As an example of the importance of the R_3 substitution on the hexahydro-s-triazine molecule, the following brief tabulation indicates the relative activity of a substituted

7
and unsubstituted compound as related to the prevention of growth of industrial degrading microorganisms:

TABLE I

R ₁	R ₂	R ₃	R ₄	Industrial Anti- microbial Activity
H	nC ₈ H ₇ nC ₈ H ₁₃	C ₆ H ₅ 4-C ₁₂ H ₂₅ C ₆ H ₄	H H	None. Good.
H				

as it will be noted from the above table the compound wherein a dodecyl function is attached to the phenyl ring exhibited strong antimicrobial activity, yet a compound absent the said function has no such activity.

It must, of course, be understood that while the aforesaid illustrative examples disclose the preparation of the hydrochloride salt, other inorganic acids such as nitric or sulfuric or organic acids such as picric or paratoluene sulfonic may be employed to yield a large number of corresponding salts either inorganic or organic.

I claim:

1. A compound selected from the group consisting of those of the formulae:

and acid addition salts thereof wherein R represents a substituent selected from the group consisting of a higher alkyl and an alkanoyl; R' represents a substituent selected from the group consisting of hydrogen and methyl and R'' represents a substituent selected from the group consisting of lower alkyl and hydroxyl lower alkyl.

2. 1 - dodecylphenyl - 2 - n - hexyl - 4,6 - diiminohexahydro-s-triazine hydrochloride.

3. 1 - dodecylphenyl - 2,2 - dimethyl - 4,6 - diiminohexahydro-s-triazine hydrochloride.

4. 1 - octadecylphenyl - 2,2 - dimethyl - 4,6 - diimino-

hexahydro-s-triazine.

5. 1 - octylphenyl - 2,2 - dimethyl - 4,6 - diimino - hexa-

hydro-s-triazine hydrochloride.

6. 1 - octanoylphenyl - 2,2-dimethyl-4,6-diimino-hexa-

hydro-s-triazine hydrochloride.
